COMBINED BASEBOARD AND CONDUIT

Charles E. Barnes, Philadelphia, Pa.

Application April 11, 1941, Serial No. 388,187

2 Claims. (Cl. 189—85)

This invention relates to a combined baseboard and conduit, and it consists in the constructions, arrangements and combinations herein described and claimed.

It is the cardinal object of the invention to provide a combined base board and conduit embodying a floating cove front, permitting the front to be adjusted to a floor which may be settled or drawn away from its anchorage.

It is also an object of the invention to provide a combined baseboard and conduit in which exposed retaining means for securing the front are eliminated.

It is a still further object of the invention to provide a floating front having means for detachable connection with the conduit, permitting ready access to electrical wires and the like housed in the conduit or conduits.

A further object of the invention is to provide a combined conduit and base board in which the conduit is securely fastened to the floor or other surface and the baseboard is vertically movable with respect thereto, eliminating separation between the floor and the baseboard.

A further object is to provide a baseboard that permanently stops draft, mice, etc. Another object is to provide a base requiring no wood grounds in plaster wall for securing base.

An important object is to provide permanent affinity of base and wall surface. This being accomplished by long leg of mounting piece being of greater angle than 90 degrees to bight and when forced into angle formed by wall and floor gives strong spring tension against wall.

Another object of my invention is to provide adequate and concealed wiring facilities to every room regardless of type of base and material customarily used for specific rooms, such as rubber, ceramic tile, asphalt tile, linoleum, wood or steel base and also one material in combination with another material.

Another important additional feature being a flush with plaster outlet box for convenience outlets, switches or jacks for portable telephone connections and slideable telescoping connecting means between it and any of the baseboards described.

Additional objects, advantages and features of invention will be apparent from the following description considered in conjunction with the accompanying drawing, wherein

Figure 1 is a cross section of a projecting type of baseboard and conduit embodying a full floating front.

Figure 2 is a cross section of a modified form shown in Figure 1.

Figure 3 is a cross section of an all-steel base and floating front similar in some respects to the construction of Figure 1, but consisting of a plurality of raceways for accommodating electrical wires, one raceway in top metal molding and one in footmold.

As has already been stated, the principal object of the invention is the provision of a closure front for base conduits which is movable independently of the base conduit in order that the front may be neatly and snugly seated against a base support thereby eliminating unsightly and undesired cracks between the base support and the front which occurs during "settling" of a building structure.

In all forms of the base-board and conduit, it will be found that the structures embody a floating front structure and in order that this may be more clearly understood, attention is first invited to Figure 1 of the drawing, wherein, a floor base 10 is shown, upon which there is secured a metallic base 11. The base 11 is substantially U-shaped as viewed in cross section, having a horizontal bight 12, a short front leg 13 and a long rear leg 14, the latter having a horizontal right angular portion 15 lying substantially parallel to the bight 12. The leg 14 is finally bent at right angles to provide a contact strip 16, the latter lying in a plane aligned with the short front leg 13.

It will be understood that the base 11 will be formed in a continuous strip mitered at the ends for snug fitting adjustment with a similar strip at the corners of a room, and at suitable spaced intervals, the bight 12 will be provided with an aperture for reception of screws or the like 17, for securing the base to a floor. Preferably, the long leg 14 will have a resilience tending to spring snugly against the wall surface 18, and this applies to all forms shown. The base being so mounted, a rigid support is provided for installation of the front, generally indicated at 19.

The front 19 is formed of sheet metal of a length complementary to the length of the base to which it is to be applied, although this is not necessary, and includes a recurved foot 20 having a planiform lower face for contacting a floor surface indicated at 21. The height of the front 19 is such as to extend above the contact strip 16 against which it snugly engages, whence it is bent inwardly into parallel relation with the portion 15 and thence downwardly as at 22, stop-

ping below the portion 15 and between the leg 14 and the wall 18.

A spring clip 23 is provided upon the inner face of the front, provided with an outwardly extended lip 24 adapted to permit ready passage of the leg 13 of the base between the clip and the front, and it should be noted that the leg terminates below the point of attachment of the clip to the front, thereby permitting vertical adjustment of the front with respect to the base 11.

By the construction of base and front as shown, raceways 25 and 26 are provided and through which electrical conductors may be extended.

As shown in Figures 1, 2 and 3, the metallic fronts are provided with "knock-out" portions 27, permitting the extension of conductors therethrough for placement of outlets or the like.

The form illustrated in Figure 2 provides for an increased number of race-ways indicated at 20 40, 42, and 43. The structure of base and front is substantially that shown in Figure 1, but the foot 20' is given a convex curvature to define the race-way 40, and an open metallic top trim 44 forms the raceway 43. This figure also illustrates a manner of conducting electrical wires from the raceways and consists of a pipe 45 opening through and secured to the leg 14, the pipe having a slip-fit with a pipe 46. By having a slip telescoping fit between the pipes, threaded connections are eliminated and further quick adjustment as to length may be accomplished.

In Figure 3 a modification of the structure of Figures 1 and 5 is shown, and in this instance the base 11 will be constructed as described in connection with Figure 1 and similarly mounted to a supporting surface or floor. The front 75 includes a right angular wall 76 arranged in parallel relation to the portion 15 of the base and a right angular portion 77 extended in the same plane as the leg 14 and aligned therewith.

The front 75 stops short of the bight 12 and is outwardly flared at its extremity as at 78. The leg 13 of the base is positioned substantially in alignment with the contact strip 16. A foot 79 is provided, in the form of a hollow moulding having a flange 80 for securing to the outer face of the front which may be accomplished by spot welding or otherwise. The moulding also includes a right angular wall 81 positioned a dis-

tance from the front 75 slightly less than the thickness of the leg 13 so as to resiliently grip the leg 13 when inserted between the wall 81 and the lower portion of the front.

5 A hollow top trim strip 44' is employed which may have any ornamental shape desired, but will include a front flange 82 for snug engagement with the face of the front and a back flange 83 for contacting engagement with a wall surface, the flange being disposed to the rear of the leg 14. Thus it will be seen that four raceways 40', 41', 42' and 43' are provided.

From the foregoing, it will be seen that I have provided a base board and conduit structure in which the front may well be said to be a "floating" one, since it is free to move so as to always snugly contact the floor surface, eliminating cracks, and thereby obviating drafts, ingress of mice, etc., to a room, as well as affording a neat, trim and sturdy structure.

While I have shown and described preferred constructions, this is by way of illustration only, and I consider as my own all such modifications in structure as fairly fall within the scope of the 25 appended claims.

I claim:

1. In a combined baseboard and conduit, a base strip having a substantially U-shaped formation in cross section defining a long leg and a short leg and a connecting bight portion, said bight portion having means for mounting upon a supporting surface, said long leg being bent adjacent its upper end to form a horizontal wall parallel to the bight portion and thence bent at right angles so as to present a portion substantially in alignment with the short leg, a front member snugly abutting the short leg and the last named portion of the long leg member, the front member extending above and overlying the horizontal wall forming a raceway, and said front member including spring tension means engaging the short leg member, whereby to permit vertical movement of the front member independently of the base.

45 2. The structure of claim 1 in which said long leg normally extends at an angle greater than 90 degrees to the bight portion, whereby to exert a strong tension against a wall surface when in operative position.

CHARLES E. BARNES.
